[57] CLAIM

The ornamental design for a disposable trash collection
receptacle, as shown and described.

DESCRIPTION

FIG. 1 is a top and front perspective view of a dispos-
able trash receptacle showing my new design;

FIG. 2 is a top plan view thereof;

FIG. 3 is a bottom plan view thereof;

FIG. 4 is a rear elevational view thereof in a collapsed
condition; and,

FIG. 5 is a top plan view of FIG. 4.

FIG. 1

FIG. 2

FIG. 3

FIG. 4

FIG. 5
